[57] CLAIM

The ornamental design for a pouring spout attachment for a paint can, as shown and described.

DESCRIPTION

FIG. 1 is a front elevational view of the pouring spout attachment for a paint can showing our new design;
FIG. 2 is a rear elevational view thereof;
FIG. 3 is a right view thereof;
FIG. 4 is a left view thereof;
FIG. 5 is a cross-sectional view taken vertically through the mid-plane of the device at line 5—5 of FIG. 1.
FIG. 6 is a top plan view thereof; and,
FIG. 7 is a bottom plan view thereof.
